Inventor
William L. Teter
By his attorney,

UNITED STATES PATENT OFFICE.

WILLIAM L. TETER, OF PHILADELPHIA, PENNSYLVANIA.

HOSE-TUBE.

SPECIFICATION forming part of Letters Patent No. 308,331, dated November 18, 1884.

Application filed May 15, 1884. (No model.)

To all whom it may concern:

Be it known that I, WILLIAM L. TETER, of the city and county of Philadelphia, and State of Pennsylvania, have invented a new and 5 useful Improvement in Hose-Tubes, of which the following is a specification.

My invention has reference to the manufacture of hose; and it consists in certain improvements in a hose formed of woven fabric 10 with longitudinal metal wires or strips bound or woven therein; further, in a hose as above set forth having its interior coated with a substance impervious to liquids, all of which is fully set forth in the following specification, 15 and shown in the accompanying drawings, which form part thereof.

The object of my invention is to greatly strengthen woven or knitted hose, whereby it may resist the effects of the great strains to 20 which it is subject in the rough usage given it, especially at fires.

By interposing members or strands non-elastic or extensible in the direction of their length among the cotton warp and weft I increase 25 its resistance to rupture and wear both longitudinally and transversely.

In the drawings, Figure 1 is a cross-section of my improved hose, showing the weft-thread where it is woven in with the outer warps. 30 Fig. 2 is a section of part of same a little farther to one side, showing the weft-thread as binding the outer and inner warps. Fig. 3 is a similar section showing the weft-thread as woven wholly with the inner warps; and Fig. 35 4 is a similar view to that shown in Fig. 2, except farther on.

The fabric of which this hose is composed is fully set forth in another pending application of mine filed August 14, 1884, and Serial 40 No. 140,503. Therefore I will simply refer to the process of weaving it briefly, the invention forming subject-matter of this application being the completed hose as an article of manufacture, and is not limited to the specific 45 manner in which the cotton is woven about the metal strands or strips.

A, as shown in Fig. 1, represents the outer woven layer of cotton. B represents the inner, woven layer of cotton, and C represents 50 the metal wires, strips, or strands which run parallel to the warp D, and are interposed

between the layers A and B, being bound therein by the weft or binding thread E. In practice it is preferable to weave a single weft or filling thread among the warps of the outer 55 and inner layers and also the warps of both in such a manner as to bind them together over the metal strips. In carrying out this principle the weft-thread is first passed between the warp of the layer A, then between 60 the shed formed by part of the warps of both the outer and inner layers, thus binding them together, as shown in Fig. 2, then through the shed formed by the warps of the inner layer, as shown in Fig. 3, and finally between the 65 shed formed by part of the warps of each layer as before, as shown in Fig. 4, and so on, the metal strips being simply tied or bound in place. If desired, the weft-thread E may be made to bind the two layers together only 70 after being woven first with each of the layers. Thus the operations shown in Fig. 2 would be omitted, but those in Fig. 4 retained, or vice versa; and it is evident that any number of 75 layers, as A and B, may be woven and bound together with the same filling or weft thread.

There are many ways of weaving or knitting a tubular fabric; hence I do not deem it necessary to further describe the manner of 80 making the tube.

The metallic wires, strips, or strands C may be of any metal; but I prefer them to be formed of flat steel, sufficiently light to be flexible, and it is immaterial to my invention how many of said strips are bound in the hose, for they may 85 be equal in number to the warp of any layer or there may be only one-half as many, the latter being preferable, as it gives sufficient strength and does not make the completed hose too heavy or stiff. When the woven 90 tube is completed, it leaves the loom in the form shown in Fig. 2, and is opened and coated on its inner surface with a layer of rubber, F, or other substance impervious to moisture; and, if desired, the entire hose may 95 be saturated with any substance impervious to moisture, in place of coating interior with a layer, F, as above set forth.

Having now described my invention, what I claim as new, and desire to secure by Letters 100 Patent, is—

1. As an article of manufacture, a woven-

hose tube formed with an inner and an outer woven layer or tube, both formed with the same continuous weft-thread, but with different warp-threads, the said weft-thread also 5 binding said tubes together, and longitudinal strengthening strips or strands of metal bound in between said layers or tubes, substantially as and for the purpose specified.

2. As an article of manufacture, a woven-
10 hose tube formed with an inner and an outer woven layer or tube, both formed with the same continuous weft-thread, but with different warp-threads, the said weft-thread also

binding said tubes together, longitudinal strengthening strips or strands of metal bound 15 in between said layers or tubes, and the interior of said compound hose coated with a substance impervious to moisture, substantially as and for the purpose specified.

In testimony of which invention I hereunto 20 set my hand.

WILLIAM L. TETER.
